(57) **CLAIM**

The ornamental design for a blender cup and lid, as shown and described.

DESCRIPTION

FIG. 1 is a front/top perspective view of a blender cup in accordance with the subject technology, shown separately without the lid for completeness of illustration.

FIG. 2 is a front view of the blender cup of FIG. 1.

FIG. 3 is a rear view of the blender cup of FIG. 1.

FIG. 4 is a left side view of the blender cup of FIG. 1.

FIG. 5 is a right side view of the blender cup of FIG. 1.

FIG. 6 is a top view of the blender cup of FIG. 1.

FIG. 7 is a bottom view of the blender cup of FIG. 1.

FIG. 8 is a front/top perspective view of a blender cup and lid in accordance with the subject technology, shown separately for completeness of illustration.

FIG. 9 is a front view of the blender cup and lid of FIG. 8.

FIG. 10 is a rear view of the blender cup and lid of FIG. 8.

FIG. 11 is a left side view of the blender cup and lid of FIG. 8.

FIG. 12 is a right side view of the blender cup and lid of FIG. 8.

FIG. 13 is a top view of the blender cup and lid of FIG. 8; and,

FIG. 14 is a bottom view of the blender cup and lid of FIG. 8.

The purpose of the broken lines shown in the drawings is to denote features of the structure that form no part of the claimed design.
